UNITED STATES PATENT OFFICE

WILLIAM REX BELL, OF TERRE HAUTE, INDIANA, ASSIGNOR TO POSTER PARTS COMPANY, OF TERRE HAUTE, INDIANA, A CORPORATION

POSTER PROCESS

Original application filed June 25, 1927, Serial No. 201,369. Patent No. 1,828,759, dated October 27, 1931.

Divided and this application filed September 9, 1931. Serial No. 561,899.

This invention relates to a process of preparing posting copy for posting purposes.

This application is a division of a prior co-pending application, Serial No. 201,369, filed June 25, 1927, entitled "Poster process and a machine therefor."

The chief object of this process is to pre-temper posting copy and have the same supplied with a uniform amount of water, whereby the same will remain uniformly tempered for a relatively long period of time and without disintegration and will be so arranged that substantially all the stretch and creases will be removed therefrom.

Another object of the invention is to prepare posting copy which has been of sheet and folded form into a form wherein all creases and folds are eliminated and the copy may be applied as a roll and secured in place by unrolling upon the pasted surface of the signboard, no pasting being required upon the surface of the copy.

The full nature of the invention will be understood from the accompanying drawings and the following description and claims:—

In the drawings, Fig. 1 is a top plan view of a moistening device satisfactory for practicing the invention.

Fig. 2 is a side elevation of the device.

Fig. 3 is a transverse sectional view taken on line 3—3 of Fig. 2 and in the direction of the arrows.

Fig. 4 is an enlarged transverse sectional view of the poster roll mounting.

The process embodying the invention may be satisfactorily employed with the apparatus illustrated in the drawings and herein-after set forth.

In the drawings 10 indicates a framework having suitable compartments 11 for reception of rolls of moistened paper posting copy, the same being wrapped in oil cloth or similar material so as to retain the moisture. A perforated support in the form of a screen or table top 12 is supported by the frame 10 and adjacent thereto is a U-shaped trough 13 in which is mounted an open bearing member 14 having the inclined slot 15 therein for receiving the end of the shaft 16. The other end of the shaft includes a universal joint

17 connected to a stub shaft 18 mounted in a bearing 19 supported by the frame 10. Shaft 18 is driven by a pulley 20 driven by a belt 21 connected to a driving pulley 22 driven by an electric motor 23 controlled by foot pedal 24 connected by link 25 to a control mechanism 26. The trough 13 is adapted to contain water or other moistening liquid and the material to be moistened is rolled under water and it has been determined that the tension in the roll obtained in rolling is sufficient to permit just sufficient moisture to be retained by the material to be moistened.

In pasting posters the copy is usually supplied in standard dimension sheets or certain sizes and multiples thereof. These sheets are supplied folded and heretofore it has been the practice to unfold these sheets in the field adjacent the posting board and moisten them with paste after moistening the board with paste, and then mounting the several sheets on the board in proper relation to form the entire sign. The present invention contemplates unfolding of each sheet at the moistening plant so that all the wrinkles and creases and folds, as well as uneven stretching, will be removed therefrom. After unfolding upon the perforated table or top 12, the bottom end of the sheet is passed into the trough and thence is wrapped around the shaft 16 and retained thereon by an elongated spring clip in the form of a partial cylinder 27, the copy sheet being represented by the numeral 28.

As the shaft 16 is rotated, the copy is passed through the tank, subjected to water and moistened to the desired degree when rolled upon the shaft. After the sheet has been entirely moistened and rolled the shaft 16 is removed through the slot 15 from the bearing 14 and elevates sufficient to permit pulling of the copy from the shaft. The rolled copy is then enclosed in an oil cloth or similar wrapper or container and then taken to the field for posting. The paper so moistened has uniform stretch. All the wrinkles and creases are removed from it and the material remains in a moistened or tempered condition suitable for easy handling and will remain in said condition for at least a day and it has remained for several days. The

resultant roll, therefore, is such that the outer end of the roll is positioned at the top of the sign board and the copy is paid out therefrom, the roll dropping by gravity and being pasted thereto without further manipulation other than the previous application of the adhesives to the board and brush pressure.

30 also indicates a similar framework supporting the motor 23 and including drawer receiving compartments 31, each being adapted to receive the full copy for one or more signs. Supported by the frame 30 is the trough 32 within which is mounted a shaft 33 in a pair of open bearings 34. Mounted on the shaft 33 are the adjustable end plates 35 guiding a roll 36 of blanking paper. The roll revolves in the tank and the paper 37 passes upwardly over a friction and severing strip 38 which is relatively smooth and serves to 10 scrape the surplus moisture from the paper 37 and such excess drips on to the drip plate 39 and is returned to the tank. The sheet 37 is rolled up upon shaft 40 mounted in an open bearing 41 at one end and having a universal connection 42 at the opposite end and the sheet is anchored to the shaft in the same manner as shown in Fig. 3 and previously described. The shaft 40 is rotated by the stub shaft 43 to which is connected said universal joint 42 and said stub shaft is rotated by the pulley 44 driven by belt 45 which is the same as belt 21, said belt passing once around the pulley 22.

35 A recording device 50 having an indicating arm 51 movable adjacent a scale 52 is associated with the shaft 40 so that the amount of blanking paper can be accurately determined in a roll and thus only sufficient paper necessary for the board of work of each sign or display will be mounted in any one roll.

40 The foregoing device is of such a nature that the employment of the perforated top permits the paper to be sprinkled when desired, the surplus dripping through, and when the paper is passed through or into the tank the surplus does not creep back along the table supporting the posting material and thus unevenly moisten the unmoistened part of the poster. If the poster were unevenly moistened, uneven stretching or creasing would subsequently form by reason of uneven stretch in it.

45 Another advantage that the foregoing arrangement secures is that in rolling the material to be posted under water the tension in the roll is such that the surplus water is crowded from the roll and only sufficient water is retained therein to completely moisten the roll but not to over-moisten the same. The following conditions are not found when the present invention is practiced, to wit, a roll having an exterior portion sufficiently moist with an interior insufficiently moist, or a roll having an interior sufficiently moist with an exterior excessively moistened, the

excessively moistened portion in either instance disintegrating when the roll is handled for pasting.

The present invention secures the tempering of poster material with just sufficient amount of moisture requisite therefor, evenly distributed and at relatively great speed and with a low labor cost. The moistened poster material then is in such shape that it can be mounted on the posting panels or boards without creasing or wrinkling and without applying glue or paste to the printed face of the posting material such as heretofore has been required.

50 After the roll has been formed of moistened or tempered paper, the same is stripped from the shaft and even though the paper be in a moistened condition the same when in rolled formation, has sufficient stability or rigidity so that it will not buckle in the roll and can be handled as if the interior were reinforced by the shaft or a supporting rod.

55 The aforesaid permits the poster copy to be damped and posted immediately, or the posting may be delayed for a week or longer. The posting may be practiced in freezing weather just so long as the moisture in the rolls is prevented from freezing and the moisture in the paste is likewise prevented from freezing. Since in prior practice, moisture in the paste has been utilized to temper the copy so that the folds and creases may be pounded out after the copy has been applied to the surface wherever physically possible so to do, a large amount of paste has been used. The present invention, therefore, permits the minimum amount of paste to be utilized, thereby effecting a further saving in material. The saving in time is effected because the paper is pretempered and the poster hangers can rapidly apply sheet after sheet in a very short time and much shorter than the previous method as required. Furthermore, the copy is left in a much better, cleaner, smoother condition, because in the old method, the copy has been applied and then has been repasted on the outer surface in order to secure proper laying.

60 The invention claimed is:

1. In posting copy the process of preparing sheet folded poster copy for posting, comprising unfolding the folded sheet, smoothing and moistening the same while unfolded and rolling the moistened sheet for simultaneously expressing surplus moisture and removing the fold wrinkles therefrom.

2. In posting copy the process of preparing sheet folded poster copy for posting, comprising unfolding the folded sheet, moistening the same and subsequently rolling the moistened sheet to the desired compactness for simultaneously expressing the surplus moisture and the fold wrinkles therefrom.

3. The process of preparing poster copy for posting comprising passing a sheet into a

moistening bath and rolling the moistened sheet to the desired compactness for expressing the surplus moisture therefrom.

4. In posting copy, the process of preparing previously folded poster copy for posting, comprising unfolding the folded sheet, smoothing the same, moistening the smoothed sheet by passing the same into a moistening liquid, and then subsequently rolling the moistened sheet in said liquid to the desired compactness for subsequently expressing the surplus moisture therefrom, the fold and wrinkles therefrom, and obtaining the desired compactness in the roll whereby uniform tempering throughout the roll is obtained.

In witness whereof, I have hereunto affixed my signature.

WILLIAM REX BELL.
